UNITED STATES PATENT OFFICE.

JOHN H. WILLIAMS, OF SPRING CITY, PENNSYLVANIA.

LOCKING DEVICE.

1,244,154.

Specification of Letters Patent. Patented Oct. 23, 1917.

Application filed July 27, 1917. Serial No. 182,689.

To all whom it may concern:

Be it known that I, JOHN H. WILLIAMS, a citizen of the United States, residing at Spring City, in the county of Chester and State of Pennsylvania, have invented certain new and useful Improvements in Locking Devices; and I do hereby declare the following to be a full, clear, and exact description of the invention, such as will enable others skilled in the art to which it appertains to make and use the same.

This invention relates to locking devices for securing certain foot levers of a motor car when the car is parked, so as to prevent it from being operated and stolen; and it consists in the novel construction and combination of the parts hereinafter fully described and claimed.

In the drawings, Figure 1 is a plan view 20 of the locking device in its normal position. Fig. 2 is a similar view but showing the device closed so as to lock the levers. Fig. 3 is a side view of the device.

A rectangular frame 2 is provided having 25 a series of parallel slots 3, 4 and 5 formed in it. These slots are of the same length, and the levers of the motor car, such as the brake lever and the transmission gear lever, project through these slots so that they can be 30 operated by foot in the usual manner. The frame 2 is secured to the usual guide plate on the floor of the car in front of the driver, through which these levers project, by means of screws 6 or any other suitable fastenings.

The frame 2 has a longitudinal undercut 35 guide bar 7 at its upper part, and three similar undercut guides 8 are formed on the bars of the frame at different distances 40 from the bar 7. A stop bar 9 is formed on the frame at the left hand side thereof.

A grid is provided comprising bars 10, 11 45 and 12 of different lengths, and connected by a top bar 14. The top bar and the ends 15 of the bars 10, 11 and 12 have beveled parts which slide in the undercut bar 7 and the guides, 8. The longest bar 10 at the left hand of the grid has a notch 16 in its left hand side.

50 A hinged latch 18 is secured to the upper part of the grid, and 20 and 21 are two staples on the frame for the latch to engage with. These staples prevent the grid from being slid laterally until the latch is

raised out of engagement with them, and any approved form of lock, such as a spring padlock is used to secure the latch in engagement with the staples.

When the grid is in its normal position, as shown in Fig. 1, all the levers can be operated. When the grid is slid to the left, as shown in Fig. 2, the notch engages with one lever, and holds it rigidly in place so that it cannot be operated in either direction. The bars 11 and 12 limit the upward movements of the other two foot levers sufficiently to prevent the car from being used, but they do not necessitate these two levers being placed in any exact position to permit the grid to be slid to the left.

When constructed in this manner, the car cannot be operated without sliding the grid to the right to free the levers, and the device is so arranged and constructed that there is no difficulty or loss of time about 75 sliding the grid to the left so as to engage with the levers.

What I claim is:

1. A locking device for foot levers, comprising a frame having parallel slots for the 80 levers to work in, and having also guides arranged crosswise of its slots, a grid or locking plate, slideable in the said guides crosswise of the slots and having parallel bars of different lengths for partially covering 85 the slots and thereby limiting the movements of the foot levers in them, and means for normally preventing the grid from sliding.

2. A locking device for levers, comprising 90 a frame having a series of parallel slots of equal length for the levers to work in, said frame having also an undercut bar at its top and undercut guides arranged at different distances from the guide bar, a grid having 95 parallel bars of different lengths provided with beveled parts which are slideable in the said guide bar and guides crosswise of the said slots, one of the bars of the grid having also a notch on one side for holding 100 one of the levers rigidly in position, and means for securing the grid from sliding when it is in the locked and unlocked positions.

In testimony whereof I have affixed my 105 signature.

JOHN H. WILLIAMS.
